VENTING MEANS

Emil O. Wirth, South Bend, Ind., assignor to Bendix Aviation Corporation, South Bend, Ind., a corporation of Delaware

Application July 17, 1943, Serial No. 495,123

3 Claims. (Cl. 277—50)

1

This invention relates to venting means and particularly to automatic pressure relief means for use in connection with fuel tanks or reservoirs of fuel supply systems.

The invention is particularly useful as a vent for the tanks of fuel systems, such for example as are used in aircraft, wherein the fuel is taken from the tanks by a fuel pump and delivered to the carburetor or other fuel proportioning device preparatory to delivery to the engine cylinder. Since fuel, such as gasoline, is volatile, a portion of the fuel tends to vaporize and escape out of the tank vent, particularly at high temperatures or low barometric pressures, with the resultant loss of fuel. Also, this tendency to vaporize causes the formation of vapor bubbles which to some extent remain entrained in the fuel and are not released until agitated or subjected to a suddenly decreased pressure as may occur at the inlet of the fuel pump. The vapor bubbles so formed tend to vapor-lock the pump, and if passed to the carburetor, tend to interfere with its operation.

The above mentioned difficulties may be at least partially overcome by the use of any pressure type of relief or vent valve, whereby the fuel vapor pressure is utilized to maintain the tank under superatmospheric pressure whenever the fuel tends to volatilize. As the fuel may be of a highly volatile nature, it is possible under various well known conditions such as high temperature and/or high altitude, to develop a high vapor pressure within the tank which may reach such a high value that there is danger of bursting the tanks. The vapor vent valve must therefore be reliable in operation, and function to release vapor whenever the pressure in the tank exceeds a safe value.

It is therefore an object of the present invention to provide a device for maintaining the fuel in a fuel tank under moderate superatmospheric pressure.

It is another object of the invention to provide a device for the relief of excess vapor pressure in a fuel system of this character and particularly of the pressure in the fuel reservoirs or tanks thereof.

It is still another object of the invention to provide a device of this character that is adapted to relieve the pressure of one or more such tanks or reservoirs.

Still another object of the invention is to provide a device of this character wherein one of the valve members comprises a fixed ball, and the other valve member comprises a movable

2

seat having an opening adapted to be closed by said ball, said other member being supported by the diaphragm, the valve being adapted to accommodate considerable misalignment of said members.

A further object of the invention is to provide a device of this character having an auxiliary valve adapted to permit air to enter the tanks to compensate for the removal of fuel and/or to compensate for the contraction of fuel which may occur under certain well known conditions.

A still further object of the invention is to provide a device of this character having a check valve arrangement adapted to prevent the escape of fuel therethrough when inverted.

The invention is further characterized by its simplicity, effectiveness and reliability, and by the means adapted to support the check valve when in its normal open position.

A further object of the invention is to provide a device of this character wherein novel improvements reside in certain details of construction and arrangements and combinations of the parts thereof.

The characteristics and advantages of the invention are further sufficiently referred to in connection with the following detailed description of the accompanying drawing, which represents a preferred embodiment thereof. After considering this example, skilled persons will understand that many variations may be made without departing from the principles disclosed; and I contemplate the employment of any structures, arrangements, or modes of operation that are properly within the scope of the appended claims.

In the drawing:

Figure 1 is an elevational view of the fuel reservoirs of a fuel delivery system having the present venting device attached to the venting pipe;

Figure 2 is a vertical section through said venting device which embodies the invention; and

Figure 3 is a plan view of the retainer ring for the check valve.

Referring more particularly to Figure 1 the fuel tanks or reservoirs are indicated generally at 10. Fuel may be taken from the tanks through conduits 12, 14 and 16, conduits 14 and 16 preferably being provided with valves 20 and 22 respectively. The upper portions of the tanks are connected together by a vent pipe 24 to which a venting device, indicated generally at 26 is attached. The venting device comprises a casing including a pair of casing members 28 and 29 between which a flexible diaphragm 30, which

may be of any well known type, is clamped, the casing members 28 and 29 being secured together by screws 32. A check valve, indicated generally at 34 is screwed into a large opening in the upper casing member 29, and the lower casing member 28 is provided with a depending, threaded nipple 36 adapted to be screwed into a suitable fixture of the vent pipe 24. There is a main venting passage through the casing which includes an enlarged portion divided by the diaphragm into an atmospheric chamber 38 and a pressure chamber 39, the latter being a chamber from which vapor under pressure may at times escape through a pressure outlet relief valve, comprising a movable valve seat member supported by the diaphragm and comprising a body 40 having a central opening 42 therein through which said vapor may pass when the valve is open. The valve seat is secured in a central opening in the diaphragm by clamping the latter between the upper surface of the body 40, which is of substantial area, and a thin metal washer 44, secured in place by turning over the free end of a tubular flange 46. In order to prevent the diaphragm from being cut and injured by the peripheral edge of said washer and the adjacent edge of the valve body 40 said washer edge is turned outwardly from the diaphragm at 48 and the edge of the valve body 40 is rounded. The fixed valve member of the pressure outlet valve comprises a ball 50, adapted to close the opening 42 in the valve member 40, said ball 50 being received in a cup-like member 52 supported within the chamber 39 by integral arms 54 which extend between the cup 52 and the interior wall of the casing member 28. The free edge portion of the cup 52 is pressed inwardly at 53 to engage the ball 50 and secure same in the cup. A spring 56, which reacts between the washer 44 and body 35 of the check valve 34, urges the valve member 40 into seating relation with the ball 50.

The casing members 28 and 29 have a laterally extending portion within which there is provided an auxiliary passage or by-pass connecting the chambers 38 and 39 and including the passages 58, 60, 62 and 64 which are controlled by a pressure inlet relief valve which comprises a plug 66 screwed into an enlarged portion of the passage 60 and having a bore 61 controlled by a valve member 68 urged to the closed position on a seat 69 by a relatively light spring 70 which reacts between said valve member 68 and a spring retainer 71 disposed within an enlargement of the bore 61 of plug 66.

The check valve 34, which prevents escape of fuel through the venting device when inverted, includes a vent passage 72 in the body 35, said passage tapering inwardly toward the atmospheric end and having a valve seat 73 adjacent said end on which a ball valve 74 is adapted to seat when the device is inverted, at which time the ball 74 assumes the dotted line position 74a. However, when the device is in its normal upright position the ball 74 is in the full-line position in the lower portion of the vent passage 72 and is supported in said position by a retaining member best shown in Figure 3, comprising an annular ring portion 78 which is split at 80, the free ends of the ring 78 being spaced apart to permit contraction of said ring for insertion in a groove provided therefor in a depending annular flange 82 formed integral with the body 35 of valve 34. Integral with said ring are a plurality of radially extending valve supporting arms 84, the length of said arms being less than the

radius of the ring 78 but of sufficient length to engage and support the ball 74.

Operation

In operation vapor pressure from the tanks 10 is conducted through the vent pipe 24 and passes into the pressure chamber 39 through a passage 36 in the nipple 36. The spring 56 is so calibrated that when the pressure in the lower portion of the chamber 38 reaches a predetermined value of, for example one or two pounds, or any other desired value, the pressure on the diaphragm 30 forces said diaphragm upwardly thereby raising the valve member 40 from engagement with the ball 50 and allowing vapor to escape through the opening 42 into the atmospheric chamber 38 from which it escapes to atmosphere through the vent passage 72. When the pressure in the tanks drops below the value for which the spring 56 is calibrated said spring returns the valve seat member 40 to seating engagement with the ball 50 thereby closing the vent, it being noted that the area of the surface of ball 50 available to close the opening 42 of the valve seat is sufficient to effect closing of said opening 42 though the valve seat may be tilted or considerably out of alignment relative to the axis of the main vent passage.

The by-pass is provided in the device to permit air to enter the tanks and compensate for the withdrawal of fuel under certain well known conditions, or to permit air to enter the tanks when the fuel cools down and contracts sufficiently to cause a partial vacuum in said tanks. Inasmuch as it is undesirable for any substantial vacuum to be built up in the tanks the spring 70, closing the by-pass valve 68, is extremely light, being only of such strength as to retain the valve in the closed position when the pressures on opposite sides thereof are substantially equal so that as soon as a slight vacuum occurs in said tanks the by-pass valve opens and relieves the vacuum.

When the venting device is in its normal upright position the ball 74 is supported by the radial arms 84 of ring 78 in such a position that vapor may pass said ball and escape through the vent passage 72, but should the device be inverted the ball 74 will drop by gravity to the seat 73 and close the atmospheric vent passage 72 thereby preventing the loss of fuel therethrough should the weight of said fuel be sufficient to open the pressure outlet valve.

While the invention has been shown embodied in a fuel system having two tanks it is thought to be obvious that said device may also be used in a system having only one tank or in a system having three or more tanks. It is also thought that the invention and many of its attendant advantages will be understood from the foregoing description, and though said invention has been illustrated and described in connection with a single embodiment thereof it will be apparent that various changes may be made in the form, construction and arrangement of the parts without departing from the spirit and scope of the invention or sacrificing all of its material advantages, the form hereinbefore described being merely a preferred embodiment.

I claim:

1. In a pressure control device for venting fuel tanks and the like: a casing comprising a pair of casing members, said casing having a main vent passage therethrough including an enlarged portion; a diaphragm clamped between the casing

members and separating the enlarged portion of the main passage into a pressure chamber and an atmospheric chamber; a fixed valve member in the pressure chamber including a spherical segment portion; a valve seat secured to the diaphragm and having a valve passage therethrough adapted to be closed by the fixed valve member; a spring in the atmospheric chamber adapted to urge the valve seat to the closed position, said spring being so calibrated that a predetermined pressure in the pressure chamber will effect opening of the pressure outlet valve; a check valve including a body portion having a vent passage therein tapering inwardly toward the atmospheric end; and a ball valve adapted to seat adjacent the smaller end of said vent passage when the device is inverted; an annular groove adjacent the larger end of the vent passage; a split retainer ring received in said groove; inwardly extending radial arms integral with said ring and adapted to support the ball member when the device is in its normal upright position and permit the passage of fluid past said ball member; a by-pass connecting the pressure chamber and the atmospheric chamber; a vacuum valve in the by-pass for controlling same; and relatively light yielding means urging the by-pass valve to the closed position.

2. In a fuel supply system including a fuel tank: a pressure control device comprising a hollow casing; a diaphragm separating the interior of the casing into a pressure chamber and an atmospheric chamber; an inlet passage communicating with the pressure chamber; a valve seat carried by the diaphragm and having an orifice therethrough; a fixed valve member in the pressure chamber, of generally spherical shape adapted to close the orifice in the valve seat; yielding means urging the valve seat to the closed position with a predetermined force; a by-pass be- 40

tween the pressure chamber and atmospheric chamber; a vacuum valve controlling the bypass; relatively light yielding means normally urging the vacuum valve to the closed position; a vent passage between the atmospheric chamber and atmosphere; and a valve adapted to close said passage upon inversion of the control device, said valve being disposed on the atmospheric side of said first and second mentioned valves, and when closed, shutting off communication between the inlet passage and atmosphere.

3. In a pressure control device for venting fuel tanks and the like: a casing having a main passage therethrough including an enlarged portion; a diaphragm separating the enlarged portion of said passage into a pressure chamber and an atmospheric chamber; a fixed valve member in the pressure chamber including a spherical segment portion; a valve seat secured to the diaphragm and having a passage therethrough adapted to be closed by the fixed valve member; yielding means adapted to urge the valve seat to the closed position; a vent passage connecting the atmospheric chamber with atmosphere, said passage tapering inwardly toward the atmospheric end; and a ball valve adapted to seat adjacent the smaller end of said vent passage when the device is inverted; a retaining member within the passage adjacent the larger end thereof; inwardly extending arms integral with the retaining member and adapted to support the ball when the device is in its normal upright position and permit the passage of fluid past said ball member; a by-pass connecting the pressure chamber and the atmospheric chamber; a vacuum valve in the by-pass for controlling same; and relatively light yielding means urging the by-pass valve to the closed position.
